UNITED STATES PATENT OFFICE.

HAROLD M. PORTER, OF HAGERSTOWN, MARYLAND, ASSIGNOR TO THE PORTER CHEMICAL COMPANY, A CORPORATION OF MARYLAND.

GAME APPARATUS.

Application filed April 7, 1921. Serial No. 459,351.

To all whom it may concern:

Be it known that I, HAROLD M. PORTER, a citizen of the United States, residing at Hagerstown, county of Washington, State 5 of Maryland, have invented certain new and useful Improvements in Game Apparatus; and I do hereby declare the following to be a full, clear, and exact description of the invention, such as will enable others skilled in 10 the art to which it appertains to make and use the same.

This invention relates to game apparatus and relates more particularly to game apparatus adapted to the playing of games which 15 will not only furnish fun and amusement, but which will also be instructive and educational in character.

One of the objects of this invention is to provide apparatus whereby games may be 20 played which will be amusing, entertaining, and instructive to both children and adults.

Another object of the invention is to provide apparatus whereby games may be 25 played by a comparatively large number of players without confusion or crowding-together of either the players or the playing pieces and which will arouse the interest of the players and incite them to keep a sharp 30 look out at all times in the game.

Another object of the invention is to provide game apparatus which is very simple and which may be produced at low cost.

Other objects and advantages of construction 35 will appear as the description proceeds.

Broadly speaking, my game apparatus comprises a plurality of playing elements or pieces consisting of a starting piece or element and other elements or game pieces bearing 40 certain symbols, characters, names, or terms bearing a certain relation to each other played in conjunction with the starting piece or element.

More specifically described, my invention 45 embodies a starter game piece having a plurality of starting faces so arranged that a comparatively large number of players may engage in the game without either the players or playing pieces being crowded together and a plurality of game elements or pieces provided with certain symbols, names or terms bearing a certain relation to each other which are to be joined or associated 50 in accordance with the existing relations.

In the accompanying drawing, I have il-

lustrated apparatus embodying the principles of my invention, but it is to be understood that this is merely one specific embodiment of the invention chosen for the purposes of illustration and is not to be considered as restrictive. 60

The drawing is a diagrammatic illustration of one mode of using my invention in playing games.

For the purposes of illustration I have 65 shown my apparatus as adapted for use in playing a game involving geography.

The elements or members comprising my game apparatus consist of a starter element or game piece, indicated generally by 10, 70 and a plurality of playing elements or game pieces 11 adapted to be set against or joined to designated faces or ends of the starter according to certain rules, to be explained later. These game pieces or elements may be 75 constructed of any suitable materials, such as hard rubber, celluloid, wood, paper, card-board, etc., but I have found it advantageous for various reasons to construct them of heavy paper or thin, flat card-board. 80

Particular attention is called to the shape of the starter piece or element 10, which is so designed that a comparatively large number of persons may use the apparatus in playing a game without crowding-together 85 of either the players or the playing pieces. The starter comprises a longitudinal body portion 12 having projections 13 extending laterally on opposite sides of the body portion. Four projections are shown, they being arranged in pairs opposite each other so that the starter is in effect double-cross-shaped. The ends of the body portion and the projections of the starter form starting faces or ends 14 against which the playing 95 pieces may be set or joined in playing the various games. The legend "Start" is preferably printed or otherwise affixed adjacent each of the starting faces or ends 14 of the starter to indicate the starting points. 100

The playing pieces or elements 11 are rectangular in shape and resemble in some respects the ordinary domino, being divided, as is a domino, on the face by a central transverse line into two portions. As has already been stated, this apparatus will be described for the purposes of illustration as involving, or giving instruction in, geography. In the specific example here involved, the players will be instructed in the 110

relations existing between States of the United States and their capitals, the particular object of the game to be described being to match or connect a State with its capital.

Each of the playing pieces 11 is provided on one of the two portions into which the face is divided with the name of a State or the capital of a State, printed or otherwise affixed thereon. In some of the playing pieces the other portion of the face is left blank and these playing pieces may be termed "half-blanks". Each of the other playing pieces has a State printed on one half-portion and a capital printed on the other half-portion of the face. The States and capitals may be affixed to the playing pieces in any desired manner best fitted to suit the convenience of the players to enable them to easily read the names, regardless of the position of the playing piece with respect to the player. In the example illustrated, on each portion of the faces of the playing pieces on which the name of either a State or capital appears, it is printed or otherwise affixed twice, in parallel lines, across the half-portion of the face, first right-side-up and then up-side-down, as viewed from one end, which makes the name of the State or capital readable from practically every angle.

In a typical example, my improved game apparatus comprises five State-blank pieces, five capital-blank pieces, forty State-capital pieces and a starter piece. It is to be understood, however, that the number and arrangement of the playing pieces may vary, the number of pieces of the apparatus illustrated changing with changes in the number of States of the United States. The number may also be considerably greater where the game pieces bear the names of countries and capitals instead of States and capitals. It is to be observed that in the present example, ten half-blank pieces have been provided while the starter piece shown has only six starting ends. The number of half-blanks is desirably larger than the number of starting ends or faces in order to increase the chances of a player being able to start the game by playing a half-blank, as more fully explained hereafter.

In playing the game described, play is started by laying down the six-ended starter. All the other game pieces or playing pieces, as they may be called, are laid face down on the table and each player draws a certain number, say five. Then any player having in his hand a half-blank may start the game by placing the blank portion against one of the faces or ends 14 of the starter. In case none of the players has a half-blank with which to start the play, each player draws in turn until someone gets a half-blank. After play has been started by the playing

of a half-blank, the next player to the left continues, by playing another half-blank on the starter or by matching the State or capital already played with its capital or State. Play is continued in this manner, building a continuous chain of playing pieces as in dominoes. Whenever a player cannot match any of the ends on the table, he draws until he obtains a playing piece to match. In case no extra playing pieces remain, a player who cannot match any of the ends on the table with the playing pieces in his possession forfeits his turn. The person first disposing of, or playing, all his playing pieces according to the foregoing rules wins the game and scores the number of points corresponding to the number of playing pieces in his opponents' possession.

Sometimes a pair of ends on the table will become blocked, that is, a State will be on one end and the capital of the State will be on another end. An example of such a situation is illustrated in the drawing in which the State of Vermont is on one of the ends and Montpelier, the capital of Vermont, is on another end. In such a case, further play on these ends is, of course, prevented. In case all six ends should become blocked, which is quite unlikely, the game is over and the player having the least number of playing pieces in his hand wins.

It will be seen that I have provided improved apparatus adaptable to the playing of various games suitable for both children and adults and that the games will furnish amusement and entertainment at the same time the players are being instructed (in the example illustrated) in the science of geography. Because of the improved construction of the starter, the players may engage in the game with comfort and without either the players or the playing pieces being crowded together. The double-cross-shaped starter affords a large number of starting points from which to build, requiring the players to keep a sharp look-out of the ends for a possible play, thereby stimulating and maintaining interest at all times.

Various changes in the form, arrangement or other details of construction may be made while still realizing the benefits of the invention.

What I claim is:

1. A game apparatus comprising a starter game piece having a plurality of blank starting faces, and a series of game pieces each bearing one or more terms adapted to be matched with a game piece bearing a different, but geographically related term, some of the game pieces of each series each having a blank face adapted to be matched with one of the blank starting faces of said starter game piece.

2. A game apparatus comprising a starter game piece having a plurality of starting

faces, and a series of game pieces each bearing one or more terms adapted to be matched with a game piece bearing a geographically related term, certain game pieces of said series of game pieces adapted to be associated with said starter game piece to initiate play.

3. A game apparatus comprising a starter game piece consisting of a longitudinal body portion having a plurality of starting projections providing starting faces, and a series of game pieces each bearing one or more terms adapted to be matched with a game piece bearing a related term, certain game pieces of said series of game pieces adapted to be associated with said starter game piece to initiate play.

4. A game apparatus comprising a plurality of game pieces consisting of a starter piece having a plurality of blank starting faces, a plurality of playing pieces each divided into two portions, one of said portions being blank and the other of said portions bearing the name of either a State or the capital of a State, and a plurality of playing pieces each divided into two portions, one of said portions bearing the name of a State and the other of said portions bearing the name of the capital of a State.

5. A game apparatus comprising a starter game piece consisting of a longitudinal body portion having a plurality of blank starting projections providing starting faces, a series of playing pieces each having a blank portion on one end and the name of a State or capital on the other end, the blank ends of the playing pieces adapted to be played on, or set against, the starting faces of the starter game piece, and other playing pieces each bearing the name of a State on one end and the name of the capital of a State on the other end adapted to be played on the first mentioned playing pieces, the various States being matched with their respective capitals.

6. A game apparatus comprising a plurality of game pieces each divided into two portions, one of said portions bearing a term adapted to be matched or connected with a

game piece bearing a geographically related name or term.

7. A game apparatus comprising a plurality of game pieces each bearing the name of a State or the capital of a State, the playing pieces adapted to be associated or connected together so that each State matches with its respective capital.

8. A game piece or element comprising a longitudinal body portion having a plurality of starting projections extending from said body portion to provide starting faces.

9. Game apparatus comprising a starter game piece having a plurality of faces, a series of game pieces each having a face related to, but different from, a face of another game piece of the series, but none of the faces of the game pieces in said series related to the faces of the starter game piece, and a second series of game pieces, each having a face related to the faces of the starter game piece and a face related to, but different from a face of a game piece of the first mentioned series, the faces of the starter game piece related to the faces of the game pieces of the second series being matched to start a plurality of courses of play, play being continued by matching the related faces of the game pieces of the first series.

10. A game apparatus comprising a starter game piece having a plurality of blank faces, a series of game pieces provided with faces each bearing a geographical term, and a second series of game pieces each having a blank face and a face bearing a geographical term, the geographical term of the first and second series of game pieces being related, the blank faces of the second series of game pieces being matched with the blank faces of the starter game piece to start a plurality of courses of play, play being continued by the matching of game pieces bearing related geographical terms.

In testimony whereof I hereunto affix my signature.

HAROLD M. PORTER.
